UNITED STATES PATENT OFFICE.

JOHN W. NASMITH, OF MANCHESTER, ENGLAND.

PROCESS FOR THE FOLDING OF CARTON BLANKS.

Application filed April 21, 1924. Serial No. 707,991.

To all whom it may concern:

Be it known that I, JOHN WILLIAM NASMITH, a subject of the King of Great Britain, and a resident of Heaton Mersey, 5 Manchester, in the county of Lancaster, England, have invented new and useful Improvements in Processes for the Folding of Carton Blanks, of which the following is a specification.

10 In apparatus as commonly used for the folding of carton blanks after the necessary creasing has been effected, the blanks are fed lengthwise into the folding machine and the flaps to be folded over are raised by inclined faces in their traverse through the machine. This of necessity calls for a very long machine, occupying much space. The object of the present invention is to fold the flaps of the carton blanks over and on to the 15 body or centre of the blank without the necessity of providing the long and space-occupying inclined faces just referred to, and to simplify the folding apparatus generally.

20 With the above objects in view my process consists in feeding the creased blanks into the folding apparatus and traversing them therethrough in a direction at right angles to the creases on which they have to be folded, the foremost flap being automatically raised and folded over on the blank centre by retaining means during the traverse of the blank, and then folding over the rear flap by positive means which operate in the direction of traverse of the blank. 25

30

35

Where a small gluing flap is provided on the edge of one of the flaps, that flap is the foremost in traversing the apparatus and it is glued by holding it momentarily in contact with a gluing roller and lifting it from said roller before the traverse of the blank brings the foremost foldable flap thereto, this lifting being automatically effected by the edges of the foremost foldable flap coming upon the means which raise them as the first step in the operation of the folding thereof.

The process with a simple and convenient form of apparatus for carrying it out 50 will now be fully described with reference to the accompanying drawings, wherein:—

55 Figure 1 is a plan of a carton blank creased ready for folding, a small gluing flap being shown attached to that foldable flap which is the first to be folded in passing through the apparatus;

Figure 2 is a side view of the carton blank after the gluing flap has been glued and the foremost foldable flap folded over;

Figure 3 is a similar view of the blank 60 when the apparatus has completed the folding;

Figure 4 is a view of the apparatus taken on a longitudinal section line and showing one of each set of a plurality of units which 65 effect the folding, rollers being shown in section where they extend across the apparatus;

Figure 5 is a plan of the apparatus employed for arresting the edge of a gluing 70 flap whilst glue is applied thereto; and

Figures 6 and 7 are details.

The drawings are not to any special scale.

Referring to the figures, the cartons, 75 ready cut and scored, are piled in a hopper of the usual kind and delivered one by one to the machine in the usual manner. The feed rollers 1, 2, and 1' and 2' pass the cartons forward. The glue tank T is of the usual kind and revolving therein is the glue 80 roller R working in conjunction with the squeezing roller S and operating as described in my British specification No. 8,263 of 1911, so that a thin but regulatable film of glue is carried round by the roller S. 85 The tank and rollers can be removed when the machine is required to fold without gluing.

Between the feed rollers 1', 2', and the roller S is a rod 3 carrying arms 4 adjustable lengthwise on the rod and to which are riveted a pair of blades 5 inclined as shown at 6. These blades are seen in plan in Figure 5 and one of them in perspective in Figure 6. The horizontal part 5 is longer 95 than the inclined part 6 and they are made in pairs. They are adjusted on the rod so that the body A B C of the carton to be operated on will pass between the inner edges of the inclined part 6, over which only 100 the end parts F of the cartons pass.

Above the blades 5 is a rod 7 free to rock in its bearings. It carries fingers 8 adjusted longitudinally thereon and positioned so as to fall between the inclined parts 6 of the blades as shown in plan in Figure 5. Means, such as the screw V, Figure 7, are provided to limit the rocking of the rod 7, so that the fingers 8 fall very close to the roller S without actually touching it. 105 On the end of the rod 7 is a lever L, Figure 7, on which is the adjustable weight W, so

that the resistance of the fingers 8 to displacement by the onward moving carton can be nicely regulated and their return to normal position assured when the carton has passed.

The function of these organs is as follows. The feed roller 1' is placed slightly forward of the centre of the roller 2' so as to direct the front edge of the carton downwards as it issues from the rollers. It passes over the horizontal part of the blade 5 and the front edge under the fingers 8, which compel the underside of the lip A to touch the roller S when this is in use. But only for an instant, because the end flaps F of the carton, riding up the inclined part 6 of the blades, raise it and cause it also to push the fingers 8 away as they offer but slight resistance. When no gluing is required and the size 20 of the carton permits they may be thrown over out of the way by turning the lever L over.

The swinging levers 9 Figure 4, are adjustable longitudinally on the free shaft 10 and are each formed with a short arm 11 resting normally against the cross bar 12 adjustable vertically in the slots 13 by the screw 14. The proximity of the lower end 30 of the levers 9 to the blades 6 can thus be regulated. They are positioned on their shaft as shown in plan Figure 5, and receive the flaps F of the carton as it passes off the inclined blades 6, giving way before it but offering some resistance by reason of the 35 spring 32 attached to a lever 28 fixed on the end of the shaft 10. Their function is to turn over the forward end B of the carton at the crease E as soon as this has passed under the fingers 8 or is free from the rollers 1', 2', when the fingers are not in use. If the lip A has been glued, the glue is now up- 40 permost. As soon as the fold has been made the doubled front edge of the carton (Figure 2) is presented naturally over the fixed plate 15 to the grip of the transporting rollers 16, 17. It will be understood that 17 and also 18 are not continuous rollers but bosses acting 45 only on the end flaps F of the cartons and adjustable lengthwise on their respective shafts M and X, to suit different widths of 50 cartons. The rollers 18, 19 carry the carton forward over the plate 20 so that the folded edge Figure 2 enters the recess 21 in the lower ends of the pendent levers 22. There 55 are a number of such levers fixed at regular intervals along the shaft 23, which is quite free to rock in its bearings 26. The lower lip of the recess 21 projects into grooves O formed in the curved front of the transverse 60 grid casting 27 which reaches right across the machine resting on slides 31 formed on the framing. It can be moved nearer to or further from the rollers 18, 19 as required and clamped in position. One or more of

the levers 22 is provided with a projection 65 24 contacting with the set screw 25 in the cross bar connecting the bearings 26. These are adjustable along the framing of the machine and are connected to the grid casting 27 by the rods 33, so that the pendent levers 70 22 can be adjusted along with the grid as desired, in relation to the rollers 18, 19, in addition to a similar but more limited adjustment by the screws 25. The advancing carton pushes the levers 22 away as it is forced 75 up the curved face of the grid 27, until the last crease D has passed over the face of the plate 20 and as soon as the flap C is free from the rollers 18, 19 it turns up to the position of the dotted line N, being lifted by 80 the teeth of flutes of the bosses 18. The carton then collapses and the rear doubled edge passes down between the face 29 of the plate 20 and the nose of the grid 27 as indicated by the arrow to the grip of the press roller 85 30, which, under spring pressure, squeezes the flap C against the lip A and, if A is glued, causes it to adhere thereto. The bosses 18 may be made either with square or angular faces flutes or teeth, or the teeth may be 90 resilient, giving way and sinking into the body of the boss when contacting with the lower roller 19. Their function is to raise the rear end of the carton and bend it at the 95 crease D so that it will collapse under the weight of the levers 22 and pass down to the press rollers, when it passes to a counting and stacking device of the ordinary kind.

I claim:

1. As a step in the preparation of a carton after the carton blank has been creased on the lines on which it is to be folded, folding the side flaps over upon the blank body by traversing the blank through an apparatus in a direction at right angles to the creases of the said blank by means of a series of rollers, raising the outer edge of the foremost flap by fixed means within the apparatus and pressing same against members which fold it over backwards upon the blank body, and raising the rear flap of the blank to collapse the latter by means operating in the direction of traverse of the blank co-acting with means against which the folded over junction of the foremost flap and blank body presses.

2. In combination with the process claimed in claim 1, gluing a gluing flap attached to the foremost flap by holding it momentarily in contact with a gluing roller and lifting it therefrom by the means for raising the foremost edge of the foldable flap, before the traverse of the carton blank brings the said foremost foldable flap to said roller.

In testimony whereof I have hereunto set 125 my hand.

J. W. NASMITH.
